CLAIM

The ornamental design for a blender base, as shown and described.

DESCRIPTION

FIG. 1 is a top right front perspective view of a blender base.

FIG. 2 is a left side elevation view thereof;

FIG. 3 is a front view thereof;

FIG. 4 is a right side elevation view thereof;

FIG. 5 is a rear view thereof; and,

FIG. 6 is a top plan view thereof.

The broken lines shown in FIGS. 1-6 are for illustrative purposes only and form no part of the claimed design.
